(57) **CLAIM**

The ornamental design for a printer, as shown and described.

DESCRIPTION

FIG. 1 is an orthographic view of a printer, showing the new design, with the printer arranged in a first arrangement, showing a first side of the printer serving as a top and a second side of the printer serving as a front that here faces to the left.

FIG. 2 is a front, left-side, and top orthographic view of the same printer in the same arrangement.

FIG. 3 is a top plan view of the printer in the first arrangement, showing the first side.

FIG. 4 is a front elevation view of the printer in the first arrangement, showing the second side.

FIG. 5 is a right-side elevation view of the printer in the first arrangement.

FIG. 6 is a rear elevation view of the printer in the first arrangement.

FIG. 7 is a left-side elevation view of the printer in the first arrangement.

FIG. 8 is a bottom, right-side, and back orthographic view of the same printer in the same arrangement.

FIG. 9 is the same orthographic view as FIG. 8, but showing an outer cover of the printer in a partially removed position.

FIG. 10 is the same orthographic view as FIG. 9, but with the outer cover in a reversed position.

FIG. 11 is the same orthographic view as FIG. 10, but with the cover installed in the reversed position; and,

FIG. 12 is an orthographic view of the same printer arranged in a second arrangement in which the cover is installed as seen in FIG. 10, and the first side serves as the front (rather than as the top) and the second side serves as the top (rather than as the front).

1 Claim, 12 Drawing Sheets
